[57] CLAIM

The ornamental design for a wood stove door with single window, as shown and described.

DESCRIPTION

FIG. 1 is a front perspective view of a wood stove door with single window, showing one embodiment of my new design; FIG. 2 is an enlarged front elevation view of FIG. 1; FIG. 3 is an enlarged rear elevation view of FIG. 1; FIG. 4 is an enlarged right-side elevation view of FIG. 1; FIG. 5 is an enlarged left-side elevation view of FIG. 1; FIG. 6 is an enlarged top plan view of FIG. 1, the bottom being substantially a mirror image of that shown; FIG. 7 is a front perspective view of a wood stove door with single window, showing a second embodiment of my new design;

FIG. 8 is an enlarged front elevation view of FIG. 7; FIG. 9 is an enlarged rear elevation view of FIG. 7; FIG. 10 is an enlarged right-side elevation view of FIG. 7; FIG. 11 is an enlarged left-side elevation view of FIG. 7; and,

FIG. 12 is an enlarged top plan view of FIG. 7, the bottom being substantially a mirror image of that shown.
